SAFETY STOOL

Wayne W. Good, Sturgis, Mich., assignor to Harter Corporation, Sturgis, Mich., a corporation of Michigan

Filed May 20, 1965, Ser. No. 85,368

Term of patent 14 years

(Cl. D15—8)

FIG. 1 is a perspective view of the stool, showing my new design.

FIG. 2 is a perspective view of the stool in folded condition.

FIG. 3 is a perspective view of the bottom of the stool in folded condition; and

FIG. 4 is a fragmentary view of one end of the stool in open condition.

The essential features of the design reside in the portion shown in solid lines.

I claim:

The ornamental design for a safety stool, substantially as shown and described.
